MOUNTING FOR LIFT TRUCK PLATFORMS

George Quayle, Philadelphia, Pa., assignor to The
Yale & Towne Manufacturing Company, Stamford,
Conn., a corporation of Connecticut

Application July 25, 1940, Serial No. 347,467

13 Claims. (Cl. 254—10)

This invention relates to a lift truck and particularly means for supporting the upwardly movable lifting platform of a lift truck. More particularly, my invention relates to linkage means for mounting the elevating platform of a lift truck relatively to the main frame of the said lift truck whereby through pivotal motion, the platform will be elevated.

Broadly, such linkage mechanism as I have devised is old and well known in the art, my construction varying from the prior art in its simplicity of design and assembly, and in its exceeding strength.

Also, as a feature of my invention, I mount the platform of my lift truck relatively to the main frame through linkage which is independent of the rear wheel mounting of the truck, thereby facilitating the utilization of wheels of varying sizes without necessarily varying the linkage connection between the platform and the main frame, as is now required.

As a further feature of my invention, my linkage mechanism, and the means whereby it is connected to the elevating platform, comprise preferably a single unit supported by bearing means relatively to the platform in a manner which facilitates assembly. Even more particularly, my linkage assembly comprises a bearing shaft on which are placed endwise movable bearing members which are then secured in spaced relation to the elevating platform. It is through these spaced bearing members that the platform bears against the shaft and the link assembly.

As a further feature of my invention, I arrange for a simple reinforcing means for my linkage mechanism. Moreover, as a further feature of my invention, I utilize this reinforcing means, which is preferably in the form of a tube extending between the links, for housing a supporting shaft for the links, the links being formed with bearing openings in which the supporting shaft rests, and the said bearing openings being preferably in communication with the bore of the tube whereby lubricating material within the tube is always available to said shaft.

I have thus described my invention somewhat generally in order that the construction thereof may be readily understood. It will, of course, be appreciated that there are further features of the invention which have not so far been set forth, but which will be described in the specification which follows and included in the claims. Moreover, the contribution of my invention may readily be embodied in varying physical forms by those skilled in the art, and I therefore expect

to obtain a monopoly which will prevent the appropriation of my invention through the use of such other forms.

Referring now to the drawings, Fig. 1 is a side elevation of a lift truck in which one form of my invention is incorporated. Fig. 2 is a section taken along lines 2—2 of Fig. 3, Fig. 3 being a plan view and partial section of the rear end of the truck of Fig. 1. Fig. 4 is a perspective view of the linkage assembly of my invention. Fig. 5 is a sectional view along lines 5—5 of Fig. 2.

Referring now more particularly to the drawings and especially Fig. 1, reference numeral 10 designates an elevating platform supported at its front end in a conventional manner relatively to a main frame 11, and with the platform being adapted for elevation by suitable means maintained within a covering member 12 carried by the platform and actuated by a lifting and steering handle 13. Actually, the lifting mechanism for the truck of my invention is shown in my co-pending application Serial No. 274,659, filed May 19, 1939. It will be understood that my invention, to be described shortly, may be utilized in any type of elevating truck having a lifting platform adapted for elevating movement relatively to supporting means.

Referring now especially to Figs. 2, 3 and 4, the elevating platform 10 is shown as supporting through suitable bolts 14 and 15, a pair of spaced bearings 16. These bearings 16 are adapted to be slipped over the ends of what I term a bearing shaft 17, the shaft being rotatable relatively to the bearings thereafter. It will be appreciated from a view of Fig. 3, that when the bearings 16 are secured to the elevating platform 10, the bearing shaft 17 can not be moved endwise relatively to the bearings, and moreover, the bearings cannot be moved off the ends of the bearing shaft itself.

Right and left hand lifting links 18 are each welded at their upper ends as at 19 to the bearing shaft 17. Gusset plates 20 are welded at 21 to the links 18, and at 22 to the bearing shaft 17, thereby assisting in securing the links to the bearing shaft and in reinforcing the union between the links and the bearing shaft.

A tube 23 is positioned between the links 18, and is welded at its ends to the links, as indicated at 24. In this way, the links 18, the tube 23, and the bearing shaft 17 form a complete unit reinforced as shown by the gussets 20. Each of the links 18 is shown bored out as at 25 for the mounting of a bearing bushing 26. The bored-out portion 25 is so formed that the bear-

ing bushing 26 will at all times be in communication with the inside of the tube 23, all as is apparent from the drawings.

A supporting shaft for the links 18 is designated by reference numeral 27, and traverses the tube 23 and the bearing bushings 26 of links 18 for mounting preferably in openings formed in side bars 11a of the main frame 11. For securing the shaft 27 against rotation, there is welded thereto as at 28 a small plate 29 which is secured through a screw 30 to the side bar 11a of the main frame 11, all as is probably best indicated in Figs. 2 and 5.

It will be well to point out at this time that the link supporting shaft 27 is maintained in endwise spaced relation to the main axle 31, on which are mounted the wheels 32 of my lift truck. Because of this relationship between the parts, it is possible to utilize varying sizes of wheels without in any way changing the relationship between the main and elevating frames, as will be quite apparent to those skilled in the art.

There is secured to the tube 23 in a conventional manner an oil or grease cup 33, through which lubricating material may be inserted into the tube 23 whereby to be maintained available at all times for use within the bushings 26, whereby the pivoting action of the links relatively to the stationary shaft 27 may be lubricated.

Referring now again to Figs. 2 and 5, it will be noted that both faces of each of the bearing portions 16 are cut away as at 16a. Actually, it is not required that both faces be cut away except to permit interchangeability of the bearings. It is the purpose of this construction to allow the gusset 22 to move as closely as possible to the bearings 16, whereby to assist in preventing deflection of the main bearing shaft.

Moreover, it will be noted that because the links 18 are placed relatively closer to one another than the points at which the shaft 17 bears on bearings 16, there will be a tendency to spread the links 18 at their upper ends. Those skilled in the art will readily appreciate that this spreading tendency is resisted by tension within the shaft 17, and therefore is quite effectively prevented. Because of this construction, a very rigid link assembly is obtained with a minimum of weight.

I now claim:

1. In a truck of the class described, a rear link assembly comprising a bearing shaft, spaced rear links each welded at one end to said bearing shaft, gussets welded between said links and said bearing shaft, a tube welded at its opposite ends to said rear links, and bearing openings in said links formed concentric with said tube.

2. In a truck of the class described, a rear link assembly comprising a bearing shaft, spaced rear links each welded at one end to said bearing shaft, a tube welded at its opposite ends to said rear links, and bearing openings in said links formed to communicate with the opening in said tube.

3. In a truck of the class described, a rear link assembly comprising a bearing shaft, rear links each welded at one end to said bearing shaft at spaced points, a tube positioned between said links and welded to the said links near the opposite ends of said rear links, bearing openings in said links formed to communicate with the opening of said tube, and a supporting shaft for said links traversing the said tube and said bearing openings.

4. In a truck of the class described, a main

frame, a lifting platform, a rear link assembly for pivotally connecting said main frame and platform comprising a bearing shaft, bearings on said platform with which said shaft cooperates, rear links welded at their upper ends to said bearing shaft, a tube welded at its opposite ends to the said links near the lower ends thereof, bearing openings in said links formed to communicate with said tube, a shaft traversing the said tube and bearing openings, and means supporting said shaft on said main frame.

5. In a truck of the class described, a main frame, a lifting platform, a rear link assembly for pivotally connecting said main frame and platform comprising a bearing shaft, circular spaced bearings on said platform through which said shaft extends, rear links welded at their upper ends to said bearing shaft, a tube welded at its opposite ends to the said links near the lower ends thereof, bearing openings in said links formed to communicate with said tube, a shaft traversing the said tube and bearing openings, and means supporting said shaft on said main frame.

6. In a truck of the class described, a main frame, a lifting platform, a rear link assembly for pivotally connecting said main frame and platform comprising a bearing shaft, circular spaced bearings on said platform through which said shaft extends, said bearings being removable from said shaft only by endwise sliding relatively to said shaft, rear links welded at their upper ends to said bearing shaft, a tube welded at its opposite ends to the said links near the lower ends thereof, bearing openings in said links formed to communicate with said tube, and a shaft supported by said main frame traversing the said tube and bearing openings.

7. In a truck of the class described, a main frame, a lifting platform, a rear link assembly for pivotally connecting said main frame and platform comprising a bearing shaft, circular spaced bearings on said platform through which said shaft extends, rear links secured at their upper ends to said bearing shaft, a tube secured at its opposite ends to the said links near the lower ends thereof, bearing openings in said links formed to communicate with said tube, and a shaft supported by said main frame traversing the said tube, and bearing openings.

8. In a truck of the class described, a main frame, a lifting platform, a rear link assembly for pivotally connecting said main frame and platform comprising a bearing shaft, circular spaced bearings insertible endwise on said shaft and then secured to said platform, rear links secured at their upper ends to said bearing shaft, bearing openings in said links formed near the lower ends of said links, and a shaft mounted on said main frame traversing the said bearing openings for supporting said links.

9. In a truck of the class described, a main frame, wheels supporting the rear end of said main frame, a lifting platform, a rear link assembly for pivotally connecting said main frame and platform comprising a bearing shaft, bearings on said platform with which said shaft cooperates, rear links welded at their upper ends to said bearing shaft, a tube welded at its opposite ends to the said links near the lower ends thereof, bearing openings in said links formed to communicate with said tube, and a shaft on said main frame spaced longitudinally relatively to the axis of rotation of said wheels and traversing the said bearing openings in said links.

and said tube, for supporting the said links on said main frame.

10. In a truck of the class described, a main frame, wheels supporting the rear end of said main frame, a lifting platform, a rear link assembly for pivotally connecting said main frame and platform comprising a bearing shaft, bearings on said platform with which said shaft cooperates, said bearings being removable from said shaft only by endwise sliding relatively to said shaft, rear links welded at their upper ends to said bearing shaft, a tube welded at its opposite ends to the said links near the lower ends thereof, bearing openings in said links formed to communicate with said tube, and a transverse shaft on said main frame spaced longitudinally relatively to the axis of rotation of said wheels, said shaft traversing the said tube and said bearing openings in said links for supporting the said links on said main frame.

11. In a truck of the class described, a main frame, wheels supporting the rear end of said main frame, a lifting platform, a rear link assembly for pivotally connecting said main frame and platform comprising a bearing shaft, bearings on said platform with which said shaft cooperates, rear links welded at their upper ends to said bearing shaft, a tube welded at its opposite ends to the said links near the lower ends thereof, bearing openings in said links formed concentric with said tube, a transverse shaft supported on said main frame and spaced longitudinally relatively to the axis of rotation of said wheels, said

5 shaft traversing the said tube and said bearing openings in said links for supporting the said links on said main frame, and means for locking said shaft against rotation relatively to said main frame.

10 12. In a truck of the class described, a main frame, a lifting platform, a rear link assembly for pivotally connecting said main frame and platform comprising a bearing shaft, spaced bearings on said platform with which the opposite end portions of said shaft cooperate, rear links welded at their upper ends to said bearing shaft and each spaced inwardly relatively to said spaced bearings, a tube welded at its opposite ends to the said links near the lower ends thereof, bearing openings in said links formed to communicate with said tube, and a shaft traversing the said tube, said bearing openings and aligned bearing openings in said main frame.

15 13. In a truck of the class described, a main frame, a lifting platform, a rear link assembly for pivotally connecting said main frame and platform comprising a bearing shaft, circular spaced bearings through which said shaft extends, horizontal and vertical ears on said bearings, bolts traversing openings in said ears and securing said bearings to said platform, rear links welded at their upper ends to said bearing shaft, bearing openings in said link, and a supporting shaft traversing the said bearing openings for supporting said links.

GEORGE QUAYLE.
